UNITED STATES PATENT OFFICE.

LOUIS SCHERZ, OF WILKES-BARRE, PENNSYLVANIA.

LAMP HOLDER FOR MINERS' CAPS.

Application filed August 6, 1924. Serial No. 730,450.

To all whom it may concern:

Be it known that I, LOUIS SCHERZ, a citizen of the United States, residing at Wilkes-Barre, in the county of Luzerne and State of Pennsylvania, have invented certain new and useful Improvements in Lamp Holders for Miners' Caps, of which the following is a specification.

10 This invention relates to improvements in lamp supports for miners' caps.

One of the objects of the present invention is to provide a lamp support so constructed that lateral tilting or swinging movement of the lamp is positively prevented.

15 One of the disadvantages possessed by the ordinary lamp holder of this type is that the hook of the ordinary lamp is so loosely connected with the support that when the head is tilted forwardly to any considerable degree, the lamp is liable to become separated from the holder. Therefore, it is another equally important object of the present invention to provide a holder having means for engagement by the hook of the lamp, 20 which means will be so constructed and located as to preclude any accidental disengagement of the lamp hook from the holder regardless of the angle to which the head may be tilted, and likewise regardless of the direction in which it may be tilted, so that readjustments of the lamp from time to time are not required as in the majority of lamp 25 holders of this class.

In the drawings:

30 Figure 1 is a vertical front to rear sectional view through the holder embodying the invention, the cap to which the holder is applied, and the lamp which is supported by the holder, being shown in elevation;

35 Figure 2 is a rear elevation of the holder removed from the cap;

Figure 3 is a top plan view of the holder, the device embodying the invention being shown in dotted lines therein.

40 In the drawings, the numeral 1 indicates in general an ordinary miner's cap having the usual crown 2 and visor 3. The lamp is indicated by the numeral 4 and is provided with the usual hook 5 which is united thereto in any suitable manner at the rear side of the water chamber of the lamp and has an upwardly extending shank portion 6, an

intermediate arcuate connecting portion 7, and a substantially straight downwardly extending bill 8. The lamp holder is indicated in general by the numeral 9 and the same may be made from a sheet metal blank having straight side margins and so formed as to provide a central portion 10 which extends perpendicularly in front of the crown 2 of the cap, a portion 11 which extends upwardly and rearwardly from the upper end of the portion 10 and is secured in the usual manner, as at 12, to the top of the crown at the front thereof, and a portion 13 which extends downwardly and forwardly from the lower end of the portion 10 and rests upon the visor 3 of the cap.

45 A plate 14 is riveted or otherwise secured upon the upper side of the portion 11 of the supporting member 9 and is provided with a channel 15 which extends in a front to rear direction and in the bottom wall of which channel there is formed an opening indicated by the numeral 16. The channel 15 is formed by stamping the intermediate portion of the plate 14, and the said channel extends through or depends through a slot 17 which is formed in the said portion 11 of the supporting member 9, the portion 10 being likewise formed with a slot 18 which constitutes a continuation of the forward end of the slot 17 as clearly shown in Figures 1 and 2 of the drawings.

50 As thus far described, the structure is old and well known upon the market. In ordinary practice the hook 5 of the lamp 4 is engaged with the holder by having its bill 8 inserted through the opening 16 in bottom of the channel 15, the curved connecting portion 7 of the hook resting in the said channel 15. However, this construction is such a one as to prevent the disadvantages which have been pointed out above, namely that the hook has merely a loose engagement with the holder and any tilting movement of the head toward either side will permit of the lamp swinging toward that side. Any tilting movement in a forward direction, of the head, will ordinarily result in the lamp becoming entirely disengaged from the holder and dropping therefrom or, in the forward tilting movement of the head, the lamp will simply pivot upon the hook and

will not be suspended in the proper position. Theoretically the shank 6 of the hook 5 is intended to engage in the slot 18 to prevent any side swinging or tilting of the lamp, but actually this is not the case as is well recognized by miners who employ holders of this type. In view of these facts, the present invention contemplates the provision of means, in combination with such a holder, for positively preventing any side swinging or tilting of the lamp or a forward swinging thereof or disengagement of the hook of the lamp from the holder, thereby overcoming the disadvantages of the present holder.

The means just referred to comprises a socket member which is indicated in general by the numeral 19 and which comprises an attaching base 20 preferably of the oblong rectangular form shown in Figure 2 which base is riveted or otherwise secured as indicated by the numeral 21, upon the rear face of the portion 10 at the upper end thereof and immediately beneath the forward end of the portion 11 of the supporting member 9. The numeral 22 indicates a vertically disposed neck which forms an integral part with the rear side of the attaching base 20 and is of the same height as the said base and projects rearwardly therefrom as best shown in Figures 1 and 2 of the drawings. A sleeve-like socket member 23 is integrally formed at the rear end of the neck 22 and is of approximately cylindrical form and provided with an axially extending bore 24 which constitutes a socket to receive the bill 8 of the hook 5, the upper end of the bore being preferably slightly forwardly flared as indicated by the numeral 40 so as to permit of more ready insertion of the extremity of the bill into the said end of the bore or socket. By reference to Figure 1 of the drawings it will be observed that the socket is substantially in alignment with the opening 16 and at this point it will be evident that when the bill of the hook is inserted through the opening 16 and into the socket 24 with the curved intermediate portion 7 of the hook seating in the channel 15, the lamp is positively precluded from swinging toward either side or having any lateral tilting movement. Furthermore, due to the engagement of the bill of the hook through the said opening 16 and in the socket 24, there can be no swinging or pivotal movement of the hook about the supporting member and consequently there can be no swinging or tilting movement of the lamp. Furthermore there can be no accidental disengagement of the hook of the lamp from the holder by reason of the fact that the member 9 being of sheet metal, possesses a greater or less degree of resiliency and the parts will be so arranged, as best illustrated in Figure 65 1 of the drawings, that after the extremity

of the bill 8 of the hook 5 has been inserted through the opening 16, the bill of the hook will engage the flared portion of the wall of the socket 24 and the said bill of the hook, being likewise resilient, will be sprung rearwardly at the time it is further inserted into the socket. In other words, while the socket and the opening 16 are substantially in vertical alinement as above pointed out, there is just sufficient relative displacement of the two on a vertical line to insure of this rearward springing of the bill of the hook and a tight frictional fit of the said bill in the socket, it being observed that on account of this manner of engaging the parts with each other, it is only necessary to forwardly flare the upper end of the said socket 24. Referring again to the statement heretofore made that the opening 16 and the socket 24 are approximately in vertical alinement, this statement is not intended to mean that the center of the opening 16 and the axis of the socket or bore 24 are in alinement perpendicularly for while the opening 16 is located opposite the upper end of the socket it is slightly displaced in a forward direction so as to, more strictly speaking, lie immediately above the forwardly flared portion 25 of the wall of the socket thus insuring of the frictional binding of the bill of the hook in the socket as previously explained.

Having thus described the invention, what is claimed as new is:

1. A lamp holder for miners' caps comprising, in combination, a supporting member for attachment to the cap and including an upright portion and a portion extending rearwardly from the upper end of the upright portion and having an opening therein, of a socket member secured to the rear side of the upright portion of the supporting member and provided with a socket opening, the first mentioned opening being slightly displaced with relation to the axis of the socket opening and located above the upper end of the said socket opening, whereby to effect a springing of the bill of a lamp hook inserted through the first mentioned opening and into the socket opening and thus cause frictional binding of the hook bill in the socket opening.

2. A lamp holder for miners' caps comprising, in combination, a supporting member for attachment to the cap and including an upright portion and a portion extending rearwardly from the upper end of the upright portion and having an opening therein, of a socket member secured to the rear side of the upright portion of the supporting member and provided with a socket opening, the first mentioned opening being slightly displaced with relation to the axis of the socket opening and located above the upper end of the said socket opening, whereby to effect a springing of the bill of a lamp

hook inserted through the first mentioned opening and into the socket opening and thus cause frictional binding of the hook bill in the socket opening, the wall of the socket opening at and adjacent the upper end of the said opening being flared in the general direction of the displacement of the first mentioned opening with relation to the axis of the socket opening whereby the extremity of the hook bill, after engagement through the first mentioned opening, will engage and be guided by the said flare of the socket opening, in entering the said opening.

In testimony whereof I affix my signature:
LOUIS SCHERZ. [I. S.]
